ATTORNEY.

UNITED STATES PATENT OFFICE.

MACK BANKS, OF CHICAGO, ILLINOIS.

MARBLE-GUN.

1,388,015.

Specification of Letters Patent. Patented Aug. 16, 1921.

Application filed April 19, 1920. Serial No. 374,977.

To all whom it may concern:

Be it known that I, MACK BANKS, a citizen of the United States, residing at Chicago, in the county of Cook and State of Illinois, have invented certain new and useful Improvements in Marble-Guns, of which the following is a specification.

This invention relates to toys and more specifically to moot guns which may be used 10 by juveniles in playing marbles instead of shooting the marble with the thumb.

An important object of the invention is to provide a gun of this type which may be readily and easily "cocked" either in a full 15 retracted position or in a half-way position in order that a missile may be discharged from the barrel of the gun with half of the ordinary force which will prove a desirable point when the toy is used in playing 20 marbles.

Another object of the invention is to provide a device of the above nature which may be placed upon the market at a minimum cost, which is strong, durable and efficient in practice.

Other objects and advantages of the invention will become apparent during the course of the following description.

In the accompanying drawings forming 30 a part of the application and wherein like numerals are employed to designate like parts throughout the several views,

Figure 1 is a side elevation of the gun.

Fig. 2 is a transverse section taken on the 35 line 2--2 of Fig. 1.

Fig. 3 is a longitudinal section through the entire gun, and

Fig. 4 is a fragmentary longitudinal section through the invention.

40 Referring to the drawings wherein for the purpose of illustration is shown the preferred embodiment of the invention, the numeral 1 designates a tubular barrel having a partition 2 located adjacent its rear 45 end, said partition being equipped with an opening for a purpose which will appear hereinafter. The breech end 3 of the barrel is equipped at each side with a rearwardly projecting apertured ear 4 to receive the

50 pivot pin 5 of a handle 6. In this manner, the handle is pivotally connected to the breech end of the barrel whereby it may be swung downwardly between the ears 4 to "cock" the gun as will be more clearly set 55 forth hereinafter.

A spring pressed plunger is mounted for

reciprocation in the barrel and includes a head 7 having a rearwardly projecting stem 8 which is surrounded by a coiled spring 9, one end of which bears against the head 7 60 while the opposite end bears upon a partition 2 for normally urging the plunger forwardly of the barrel. The stem 8 projects through the opening in the partition to extend into the breech end of the barrel 65 a substantial distance and terminates in a laterally or downwardly projecting extension 10 as most clearly seen in Fig. 3. The arched portion of a U-shaped rod 11 engages the forward edge of the extension 10 70 while the free ends of the U-shaped rod are secured as at 12 to the relative upper portion of the handle 6 so that when the handle is swung downwardly or to cock the gun, the rod 11 pulls rearwardly upon the plunger 10 in a manner well understood. A stop element 13 in the form of a disk is secured to the plunger stem adjacent its rear end and acts to limit the forward movement of the plunger by abutting with the partition 2. 75

In order that the plunger may be releasably retained in a half-retracted position in order that a missile may be projected from the gun with half of the usual force, the 85 barrel is provided with a lateral opening 14 through which projects the annular end 15 of a bell-crank lever 16 the latter being pivotally associated with the exterior of the barrel. In this manner, the angular end 15 90 of the bell-crank may project through the opening 14 to engage the plunger head and releasably hold the same under the influence of the spring 9. A coiled spring 17 is connected with the barrel and the bell-crank 95 lever to normally urge the bell-crank lever to a position whereby the angular end 15 is projected through the opening 14 in the barrel to extend into the latter. A wire or rod 18 is connected to one arm of the bell-crank lever and with a trigger 19, so that when the trigger is pulled, the bell-crank lever will be actuated against the tension of the spring 17 to release the plunger. The trigger 19 is pivotally mounted within the 100 breech end of the barrel in the well known manner and is provided with a well known catch portion 20 which engages with the free end of the lateral extension 10 of the plunger stem. A spring 21 normally retains the 105 trigger in cocked position for when the extension 10 of the plunger rod moves rear-

wardly it engages the end of the trigger and depresses the same whereby the trigger will immediately spring outwardly to maintain the plunger in a retracted position. An opening 22 is provided in the breech end of the barrel at the side thereof to secure the end of the rod 18 which is normally connected to the trigger when it is not desired to use this attachment.

10 The relative bottom of the barrel 1 is equipped with a pair of longitudinally spaced openings 23 through which project the free ends of a yieldable or resilient flat spring 24 disposed within the barrel to normally maintain a marble in engagement with the top of the barrel so as to prevent the marble from accidental displacement when the gun is aimed downwardly toward the ground. One free end of the spring is secured to the exterior of the barrel by a rivet or other suitable means, while the opposite end is free to work through its respective opening 23.

In practice, a marble is inserted in the 25 barrel of a gun, after which the handle 6 is cocked to bring the lateral extension 10 of the plunger pin into engagement with the catch of the trigger 20. When the handle 6 is swung to a set position, the rod 11 will 30 move forwardly in the breech end of the barrel and permit the extension 10 to remain in engagement with the trigger. As explained heretofore, due to the spring 24, the marble is prevented from accidental 35 placement from the barrel while the gun is being aimed. However, when it is desired to discharge the gun, the trigger is pulled in the usual manner which releases its engagement with the extension 10 and 40 permits the plunger to spring forwardly under the influence of the spring 9 to project the marble from the barrel.

When it is only desired to cock the gun so that the plunger will only spring forward

with half of its usual force, the rear end of 45 the rod 18 is associated with an opening 26 in the trigger after the handle has been cocked to retract the plunger head 7 sufficiently to engage the angular end 15 of the bell-crank 16. The spring 17 of course maintains the 50 portion 15 of the bell-crank in a position to retain the plunger in a retracted position. However, when the device is used in this manner, it is understood that the extension 10 of the plunger does not engage with the 55 trigger. Therefore, when the trigger is pulled the rod 18 moves rearwardly to withdraw the angular portion 15 of the bell-crank from in front of the plunger head 7 to permit the plunger to move forwardly 60 under the influence of the spring.

The foregoing description and the drawing has reference to the preferred or approved form of my invention. It is to be understood however that such changes in 65 construction and combination of parts, materials, dimensions, etc., may be made as may prove expedient and fall within the scope of the appended claim.

Having thus fully described my invention 70 what I claim as new and desire to secure by Letters Patent is:—

A toy gun comprising a barrel having an opening therein between its ends, a spring 75 pressed plunger in said barrel and including a head, a spring pressed sear pivoted exteriorly to the barrel and having an end projectable through said opening for releasably engaging said head, a trigger, and a rod connected to said sear and detachably connected to said trigger.

In testimony whereof I affix my signature in presence of two witnesses.

MACK BANKS.
